UNITED STATES PATENT OFFICE.

EDWARD J. STEPHENS AND HIRAM E. GREEN, OF PAWTUCKET, R. I.

MACHINE FOR PRINTING YARN.

Specification forming part of Letters Patent No. 57,592, dated August 28, 1866.

To all whom it may concern:

Be it known that we, EDW. J. STEPHENS and HIRAM E. GREEN, of Pawtucket, in the county of Providence and State of Rhode Island, have invented a new and Improved Machine for Printing Yarn; and we do hereby declare that the following is a full, clear, and exact description thereof, which will enable others skilled in the art to make and use the same, reference being had to the accompanying drawings, forming part of this specification, in which—

Figure 1 represents a longitudinal vertical section of this invention, taken in the plane indicated by the line $x x$, Fig. 2. Fig. 2 is a plan or top view of the same.

Similar letters of reference indicate like parts.

This invention relates to an improvement in that class of machines on which a patent has been granted to us March 14, 1865.

Our present invention consists in printing yarn by means of one fluted and one plain roller, the fluted roller being provided with the requisite quantity of color from a suitable box or trough.

The yarn in passing through between the two rollers is printed simultaneously on both sides, and it takes up the color from the high parts or ridges of the fluted roller and from those parts of the smooth roller which come opposite said ridges as said rollers revolve. The color on the plain roller is spread by the action of an additional roller, which is covered with felt, cloth, or other textile or soft material, and which bears hard on the surface of the plain roller in such a manner that by the action of the soft or elastic covering the color on the plain roller is spread into a thin film, all the surplus color being forced off at the ends, where it collects in suitable troughs.

A represents a frame of wood or any other suitable material, which forms the bearings for the axles of the printing-rollers B B', the spreading-roller C C', and the color-roller D, which takes up the color from the trough E and transmits it to the roller C', by which it is transferred onto the surface of the fluted printing-roller B'. These three rollers B' C' D are geared together by suitable cog-wheels, and they may or may not be geared together with the two remaining rollers B C.

The roller B is plain, and its boxes *a* are

made to slide on the frame, so that said roller can be set up against the surface of the fluted roller, and it is adjusted in the desired position by the set-screws *b*. Said plain roller is supplied with color from the fluted roller, and the color thus supplied to it is spread in a thin film by the action of the roller C, which is covered with felt, cloth, india-rubber, or other textile or elastic material, and which is set up against the surface of the plain roller B by means of set-screws *c*. By the action of this roller all the surplus color transferred to the plain roller B from the roller B' is squeezed off over the the ends, and just enough is left on the surface of said plain roller to produce the desired effect.

The yarn in passing through between the two rollers is exposed to a pressure only on those parts where it comes between one of the ridges of the fluted roller and the surface of the plain roller, the intervening parts being left uncolored, and the operation of printing the yarn is greatly facilitated.

When two fluted rollers are used, said rollers must be made exactly of the same diameter, and arranged to revolve with exactly the same superficial speed, so that the ridges of one roller are opposite those of the other. But, if one of the printing-rollers is plain, no particular care need be taken in regard to size or speed of such rollers, and the printing is effected in an easy manner, provided the roller C, which serves to spread the color on the plain roller, is in the proper condition.

The color squeezed off over the ends of the rollers B C collects in troughs F, which are movable, so that the color can be conveniently transferred back to the trough E whenever it may be necessary.

What we claim as new, and desire to secure by Letters Patent, is—

The use, in machines for printing yarn, of the plain roller B and fluted roller B', in combination with each other and with suitable color-rollers, substantially as and for the purpose set forth.

EDWARD J. STEPHENS.
HIRAM E. GREEN.
